UNITED STATES PATENT OFFICE.

JULIUS B. WANTZ, OF CHICAGO, ILLINOIS, ASSIGNOR TO VICTOR X-RAY CORPORATION, OF CHICAGO, ILLINOIS, A CORPORATION OF NEW YORK.

X-RAY APPARATUS.

Application filed February 11, 1922. Serial No. 535,742.

My invention relates to X-ray apparatus designed, more particularly, for use in both fluoroscopic and radiographic work, though certain features of the apparatus may be used in apparatus intended for fluoroscopic work only and others in apparatus restricted to use in radiographic work; and my object generally stated is to provide improvements in such apparatus to the end that they may be more economically constructed, be of simplified construction, be adapted for greater flexibility of use under the conditions presented in practice, and in general to adapt the apparatus to better perform the functions for which such apparatus is provided.

More specifically my objects are to provide, in a fluoroscopic apparatus, for the simultaneous adjustment of the tube and fluorescent screen along the table supporting the patient to be observed; to provide for the shifting of the screen into any desired position relative to the tube in order that the anatomy of the patient may be observed from the various positions rendered desirable; to provide, more especially in a structure wherein the table for the patient is mounted to swing in a substantially vertical plane toward and away from substantially horizontal position, a tube-holding-and-shielding device which shall be of economical construction and of light weight, thereby to reduce the cost of construction and render these parts readily shiftable and counterweighted by a relatively light weight; to provide for the swinging of the tube in a plane lengthwise of the table; to provide for the shifting of the screen in a plane generally parallel with the table in order that a screen of a given dimension may present the maximum capacity for use, and shifted, if desired, to a position permitting the operator free access to the patient for manipulation; to provide, in a combined radiographic and fluoroscopic table, for the supporting of the plates in a manner adapting the supports to be moved out of a position in which they obstruct the apparatus for fluoroscopic work; to provide for the easy assembly of the counterweights carried by the table-portion of the apparatus, with the parts to be counter-balanced thereby and without requiring skill on the part of the one assembling the parts; and other objects as will be manifest from the following description.

Referring to the accompanying drawings: Figure 1 is a view in side elevation of a combined fluoroscopic and radiographic X-ray apparatus constructed in accordance with my invention, portions thereof being broken away. Figure 2 is an end view of the apparatus. Figure 3 is a plan view thereof with the tube-stand and the parts at one end of the apparatus shown in plan section. Figure 4 is a bottom plan view of the table-top portion of the apparatus and the parts carried thereby. Figure 5 is an enlarged sectional view taken at the line 5-5 on Fig. 1 and viewed in the direction of the arrows. Figure 6 is an enlarged section taken at the line 6-6 on Fig. 4 and viewed in the direction of the arrows. Figure 7 is an enlarged bottom plan view of one of the corner portions of the table-top with certain parts broken away; and Figure 8, a plan view of the intermediate portion of the table-top and screen showing the latter adjusted into one of the positions it may occupy in use.

In the particular construction shown, the frame for supporting the table-top and the tube-holder is formed of the upwardly-extending side-frames 9 spaced apart, and connected together at their lower portions by a bolt 10 surrounded by a spacer-tube 11 located between the frames 9 and at their upper ends by a bolt 12; upper and lower bars 14 and 15 at opposite sides of the frame secured at their right hand ends (Fig. 1) in lugs 16 and 17, respectively, to the frame-sides 9 and at the left-hand ends in a cross-frame 18, the frames 9 and 18 being equipped with casters 19 and 20, respectively. The frame also comprises an end frame structure connected with the cross-frame 18 and formed with hollow posts, or masts, 21, as is common in constructions of this kind, for receiving the wires leading to the tubes hereinafter referred to, and a tube-stand-supporting frame-like structure comprising an upright 22, at the right hand end of the apparatus in Fig. 1, provided with a caster 23, and upper and lower bars 24 and 25 extending lengthwise of the apparatus and connected at one end of the structure with the upright 22, and at the opposite end of the structure with the cross-frame 18 by brackets 26 and 26^a, the lower bar 25 being connected with the side-frame 9 by a bracket 27.

The table-top for supporting the patient is shown at 28 and is pivoted between its ends, preferably to one side of its center, on the bolt 10, adapting the table-top to 5 swing in a substantially vertical plane between the side-frames 9, the plate-portion of the table-top, viz, the portion thereof on which the patient rests, being constructed of any suitable material transparent to 10 X-rays. The table top 28 is provided at one side with a depending curved bar 30 containing openings 31 at intervals adapted to receive the inner ends of a spring plunger 31^a mounted in the frame-sides 9 by means 15 of which the table-top is held in any desired position of adjustment on the cross-bolt 12. The table-top comprises the parallel bars 32 shown as provided along their inner edges with ribs 33, and pieces 34 extending crosswise of the table top and to 20 which the bars 32 are connected at the ends of the latter, and the upper plate-like portion 35, hereinbefore referred to and upon which the patient is supported, the portion 25 35 of the table top being disposed in spaced relation to the bars 32 and being supported from the latter at intervals by means of the depending members 36 arranged at opposite sides of the table.

Generally stated the table-top carries an X-ray tube holder mounted thereon to be moved lengthwise of the table top at the under side thereof, for use in fluoroscopic work and a fluorescent screen supported to 30 extend above the table-top and be movable along the latter, this screen cooperating with the tube in the holder just referred to and through the medium of which the operator makes the desired observations of 35 the patient, these parts, where the table top is supported in a manner to permit it to be adjusted into different positions in a substantially vertical plane, as in the construction shown, being suitably substantially 40 counterbalanced, to render these parts movable into different positions of adjustment, with comparative ease, and without danger of injury to the apparatus. In the particular construction shown, the tube holder 45 and screen are supported on a carriage represented generally at 37 and shown as formed of a pair of side bars 38 and 39, and cross rods 40 and 41 connected together and forming a rigid frame-like structure 50 which is located at the under side of the table top 28, this carriage being provided with grooved rollers 42 and 43 which engage, at their grooves, with the ribs 33 of the bars 32, along which latter they are 55 movable, being held against disengagement therefrom by the engagement of the walls of the grooves in these rollers, with the ribs 33. The tube-holder for the tube to be used in radiographic work, and located 60 below the portion 35 of the table top, is 65 in the form of a frame comprising side members 44 extending lengthwise of the table and cross-bars 45 connected at their opposite ends with depending lugs 46 on the side members 44, the side members 44 being provided with laterally-extending portions 47 at which the holder is pivotally supported between its ends on trunnions 48 carried by depending bosses 49 on the side bars 38 and 39, whereby the tube holder now 70 being described is pivotally supported at its medial line on an axis extending crosswise of the table. Mounted on the rods 45 to be movable crosswise of the table in a plane substantially parallel with the portion 35 of the latter, is a plate-like member 50 equipped at opposed edges with grooved rollers 51 which partially embrace the outer surfaces of the rods 45 and while confining the plate portion 50 thereon, against accidental engagement therefrom, permit the member 50 to be moved along these rods into different positions of adjustment thereon. The member 50 is provided with any suitable means for dependingly supporting 75 thereon the X-ray tube which, in accordance with the construction shown, is confined within a shield represented generally at 52 constructed of current-insulating material such as lead glass, and opaque to 80 X-rays, the tube being held in position through the medium of any suitable form of clamps represented generally at 53 carried by the member 50 and engaging the contracted ends of the shield 52. The portion 50 contains an opening therethrough (not shown) located centrally thereof and with which a cylindrical tube 50^a communicates and opposite to which the central portion of the tube in the shield 52 extends, the shield also containing an opening registering with the end of the tube 50^a, the portion 50 being provided with an upwardly-flaring ray-confining member 54 registering at its lower open end with the above-referred-to opening in the portion 50. The apparatus shown is also equipped with shutter or diaphragm mechanism cooperating with the opening in the member 50 under the control of the operator for varying the size of the opening through which the rays emitted from the tube pass to the patient. Such mechanism may be of any suitable form, and, by way of example, the form shown in United States Patent No. 1,242,498 granted to me October 9, 1917, may be employed. The rods, through the medium of which the two sets of shutter or diaphragm members are separately operated, are represented at 55 and 56, and the separately rotatable elements, through the medium of which these rods are operated, are represented at 57 and 58, and supported on a frame formed of the rods 59, a cross-bar 60 connected with these rods, and a tu- 115 120 125 130

bular journaling member 61 connected with the cross-bar 60 and extending upwardly and in which the rotatable element 58 is journaled, this frame being connected with 5 the member 50, at the ends of the rods 59 opposite those at which they are connected with the cross-bar 60.

The tube referred to, the ends of which are shown as projecting beyond the ends 10 of the shield 52, in Fig. 4, is supported in the shield in any desirable manner as is well understood in the art. The shield 52, in addition to being opaque to X-rays as stated, is also made opaque to ordinary light 15 rays as by surfacing it with a material opaque to ordinary light rays, or providing in the material of which the shield is made a material opaque to ordinary light rays. The shield 52 is shown as formed of two 20 similar sections 62 which abut endwise together adjacent the center of the tube and are secured together through the medium of bolts, one of which is shown at 63 engaging lugs 64, on these sections, the 25 shield being of substantially the same shape as the X-ray tube located therein, and extending throughout its extent, into relatively close proximity to the tube, whereby the shield, while functioning in a highly de- 30 sirable manner to prevent the emission of rays from the tube, except through the opening in the pipe 50, thus protecting the operator and maintaining the room in which the apparatus is located, in relatively dark 35 condition, necessary for the most effective fluoroscopic work, is relatively light in weight, which is a decided advantage in that the supporting parts may be made correspondingly lighter in weight, and in the 40 case of a pivoted table top, as in the construction shown, where it is desired to counterbalance the moving parts, the counterweighting mechanism may be made much lighter in weight.

45 The fluorescent screen, hereinbefore referred to and which may be of a construction as commonly provided, is represented at 65 and is shown as mounted in a frame 66 which is supported from the carriage 37 by the following described construction. The construction referred to comprises a 50 pair of parallel rods 67 which extend cross-wise of the apparatus and are confined, and supported, in guides 68 at the underside of 55 the side member 39 of the carriage 37, set-screws 69 screwing into these guide portions and against the rods 67, serving to hold the latter in lengthwise adjusted position. The outer ends of the rods 67 are connected together by means of a cross-bar 70 from 60 which rises, the upright, parallel, bars 71 connected together at their upper ends by a cross-piece 72. The rods 71 provide a guiding support for a frame 73 provided at its 65 opposite edges with upper and lower sets

of grooved rollers 74 journaled thereon and between which the upright rods 71 extend, the frame 73 being movable up and down on the rods 71 at the rollers 74. The frame 73 is formed at its upper end with a yoke-shaped portion 75 which extends substantially horizontally, the arms of the yoke, which are represented at 76, extending in a direction toward the table top, and the cross-bar 77 of the yoke extending lengthwise of 75 the table top. Located within the yoke 75 and pivotally supported on the arms 76, at the pins 78, is a member 79 provided along one edge with a lug 80 which extends directly beneath the cross-bar 77 and serves as a 80 stop, when engaging the underside of the cross-bar 77, to prevent the member 79 from rotating in one direction, beyond a predetermined point. The member 79 is provided with an extended portion 81 forming a support 85 for a bearing member 82, the latter being pivotally connected therewith, by the pivot pin 83 which extends in a plane transverse to the axis about which the member 79 is movable. The bearing member 82 90 contains a slot 84 extending lengthwise thereof and into which a journaling portion 85 of a yoke-shaped frame 86, extends and is journaled, to adapt the frame 86 to pivot on the member 82, the journaling portion 95 85 being located midway between the arms 87 of the frame 86. The screen 65 extends at one end into the yoke 86 as shown, the extremities of the arms 87 preferably reaching to a point substantially midway between 100 the ends of the opposed sides of the frame 66 and with which the latter is pivotally connected, as by the pivots 88, to adapt the screen to be rocked in the frame 86.

From the foregoing it will be noted that 105 the screen is connected with the frame 73 in a manner to permit the screen to have universal movement on this frame, adapting the screen to be moved into any position desired by the operator, as conditions may 110 require, in the observing of the patient to the greatest advantage, the feature of affording the pivot 83 being of advantage as it enables the screen to be adjusted into different angular positions in a plane or planes 115 extending substantially parallel with the table top, one of the positions to which it may be adjusted being shown in Fig. 8, and thereby enhancing the field of vision afforded 120 by the screen, as compared with the field presented by the screen when it extends at right angles to the median line of the table top. The pivoting of the member 79 on the frame 73, at the pivot 78, adapts the member 79 and the parts carried thereby, to be swung 125 upwardly and to the right in Fig. 2 into a position in which the screen is removed from a position directly above the table top, which is desirable when the apparatus is 130 used for radiographic work. The vertical

adjustment of the frame 73 on the rods 71 adapts the screen to be raised and lowered relative to the table top, as conditions may require, the location of the parts carried by the frame 73, being to one side of the plane of the rollers 74, operating to exert sufficient friction between the parts to hold the frame 73 and the parts carried thereby in vertically adjusted position.

10 Means are provided for substantially counter-balancing the carriage 37 and the various parts carried thereby, as hereinbefore described, in order that this carriage, with the parts thereon, may be shifted with ease, into different positions lengthwise of the table, regardless of the position occupied by the table in the adjustment of the latter on the trunnions 48, the particular construction of counterbalancing means for the purpose stated, and shown in the drawings, comprising two sets of pulleys 89 and 90 journaled at the under side of the table-top toward its opposite ends, as represented, cables 91 and 91^a, each of the cables 91 connecting at one end, as indicated at 92, with the carriage 37; and a weight structure represented generally at 93 and in the form of a holder to the ends of which one end of each of the cables 91^a is attached, as indicated at 94, the cables 91 connecting at their other ends with the ends of the holder 93, as indicated at 93^a and the other ends of the cables 91^a being connected with the carriage 37 at the end thereof opposite that at which the cables 91 connect therewith, as indicated at 92^a. The cables 91 from their points of connection with the carriage 37 extend lengthwise of the table in a direction toward the left-hand side of Fig. 4, thence extend partway around the pulleys 89 and thence in the opposite direction, lengthwise of the table. The cables 91^a extend from the points of connection 94 with the counterbalancing structure 93 to the right in Fig. 4, thence partially around the pulleys 90 and from the latter to the left in this figure to their points of connection with the carriage 37 at 92^a. By virtue of the connections just described, the carriage 37 and the parts carried thereby, and the counterbalancing structure 93, move lengthwise of the table in unison, but in opposite directions, to perform the counterbalancing function.

55 The counterbalancing structure 93 is shown as formed of a U-shaped section 95, which may be a sheet of metal bent into the form shown in Fig. 5 to provide the legs 96 which extend parallel with each other, and the cross-connecting portion 97, this holder section being adapted to have applied thereto the weights represented at 98 and shown as extending parallel with each other and in spaced relation and be secured to the holder section 95, as by means of bars 99 extending crosswise of the weights 98,

the bars 99 preferably having lips 100 at their ends at which they overlap the outer sides of the weights 98, and be secured in position to prevent displacement of the weights, as by means of the bolts represented at 101 shown as extending thru the portion 97 with which the heads of the bolts engage, and at their threaded ends thru the bars 99, nuts 102 being screwed upon the threaded ends of these bolts and against the bars 99 for holding the weights 98 in place.

15 The holder section 95 is provided at each end with three rollers 103, 104 and 105, the rollers 104 being located between the rollers 103 and 105, and offset therefrom, as shown more particularly in Fig. 5, these rollers being disposed at opposite sides of guide bars 106 shown as parallel and extending lengthwise of the table structure and forming guides along which the counterbalancing structure is movable, the rods 106 being secured at one end to the end cross-frame 34, at the right-hand end of Fig. 4, and at the opposite end to a cross-bar 107 secured to the side members 32 forming a part of the frame of the table-top.

20 The connection between the X-ray tube, which is of the so-called "hot filament" type, in the particular construction illustrated, and the source of low potential current and high potential current may be in accordance with common practice, the representation in the drawings, of such connections, being somewhat diagrammatic. In this connection, it may be stated that the 100 cathode end of the tube, which is at the right-hand side of Fig. 1 and which includes the "hot filament" referred to, is connected with two wires represented at 108 and 109 which lead thru an insulator tube 110 extending lengthwise of the table and supported in a position below the tube-holder in depending brackets 111 carried by the plate 50, these wires leading thence into one of the hollow masts 21, there being preferably interposed in these wires, in accordance with common practice, reel devices (not shown) carried by the main frame of the apparatus and operating to automatically take up any slack in the wires and still permit the wires to pay out in the movement of the various parts of the apparatus, without disturbing the circuit connections. A high potential wire, represented at 112, leads from the anode end of the tube, shown as equipped with a radiator, into the other one of the masts 21, this wire also having a reel device (not shown) interposed therein and functioning as stated of the reel devices above referred to. The two wires 108 and 109 connect with any suitable source of low potential current and the wire 112 and one of the wires 108 and 109 connect with any source of high potential current.

25 The apparatus as shown is adapted, as 130

hereinbefore stated, for radiographic work, and to this end provision is made for supporting an X-ray tube in position above the table top and adapting it to be moved along the latter and providing other movements of the tube desirable for the production of radiographs under the various conditions presented in practice. The tube-supporting mechanism just referred to is shown as formed of an upright tubular member 113 and tube-holding mechanism represented at 114 which engages the member 113 and has movement vertically thereon, the mechanism 114 being controlled by counterweight mechanism on the upright 113 the cable of which, represented at 115, connects with the mechanism 114 and with a counterweight (not shown) vertically movable in the upright 113, the mechanism 114, which supports an X-ray tube represented at 116, providing for movement of this tube crosswise of the table, and also for a variety of rocking movements. The tube-supporting mechanism referred to as shown is of the general construction shown and described in United States Letters Patent No. 1,239,145 granted to me September 4, 1917, and therefore detailed description of this mechanism is not necessary.

The column member 113 is supported, to be movable along the table, on the bars 24 and 25, and to this end is provided at its lower end with a head 117 equipped with peripherally grooved rollers 118 and 119 vertically spaced apart and rollingly engaging the bar 25 at its upper and lower portions, respectively, and between its ends with a head 120 equipped with rollers 121 and 122 which rollingly engage the bar 24 at opposite portions of the latter, as shown.

The table top is shown as adapted to receive the sensitized plates for the making of the radiographs, the arrangement shown providing for the insertion of the plates to position on the table top by telescoping them therewith from a side of the table. To this end the table top, shown adapted for supporting two plates disposed in a series extending lengthwise of the table, is provided with plate-holder-receiving grooves 123 which extend crosswise of the table top, these grooves being provided in the end frame member 34, the cross member 107 and in a cross-member 124 located midway of, and parallel to, the members 34 and 107, the member 124 being pivotally connected at one end, as represented at 125, to a bracket 126 connected with one of the side bars 32 and containing in its opposite end a sprung pressed plunger 127 adapted to enter an opening in a lug 128 on the table top when the member 124 occupies the position shown in Fig. 4, each of the members 34 and 107 containing one of the grooves 123 which open toward each other, and the member 124

containing two of these grooves which are parallel with the grooves in the members 34 and 107 and open toward the latter, respectively. The members 34, 107 and 124 are provided, intermediate their ends, with lugs 129 disposed below the plane of the grooves 123 and extending laterally thereof, as shown, these lugs forming supports for the inner ends of leaf springs 130 which are connected at their outer ends with lugs 131 on, and extending laterally from, the members 34, 107 and 124, these springs, which are upwardly bowed between their ends as shown, extending parallel with the members 34, 107 and 124 and extending into the path of plate-holders represented at 132 and carrying the sensitized plates, the one shown being represented at 133 (Fig. 6), these plates being held in place on the holders 132, by clips 134 located at the corners of the plates. From the foregoing it will be readily understood that the plate-holders 132, with the plates 133 therein, are introduced to position into the table by sliding them, transversely of the table, into the opposed grooves 123 and against the upper surfaces of the springs 130 beneath them. The cross-bar 124 is pivotally supported, as stated, to adapt it to be bodily swung on its pivot 124 into a position in which it generally parallels one of the side bars 32 of the apparatus (see Fig. 7), in which position it offers no obstruction to the passage of the rays from the tube, beneath the table, into the patient above the table, in the use of the apparatus for fluoroscopic work. Thus the table top, while being provided with cross guides for the sensitized plates in connection with radiographs, may be used to the maximum advantage in fluoroscopic work.

While I have illustrated and described a particular construction embodying my invention, I do not wish to be understood as intending to limit it thereto, as the same may be variously modified and altered without departing from the spirit of my invention.

What I claim as new, and desire to secure by Letters Patent, is:

1. In an X-ray photographic and fluoroscopic table comprising a stand, a patient's support having a transverse pivotal mounting in said stand, a fluorescent screen on the upper side of said support and movable therealong, and a tube-supporting member and tube at the opposite and under side of said support and adapted to be moved lengthwise thereof, said tube-supporting member having a tiltable tube holding portion adapting said tube and tube holding portion to adjustment angularly to said patient's support and to said screen.
2. An X-ray photographic and fluoroscopic table comprising a stand, a patient's

support transparent to X-light transversely journaled in said stand and adapted to be moved in a vertical plane, a track upon the under side of said support, an X-ray tube-supporting member upon said track, and an X-ray tube in said member, said member having a tiltable tube-holding portion adjustable angularly to said support whereby X-light from said tube may be made to penetrate said support at angles other than right angles.

3. An X-ray photographic and fluoroscopic table comprising a stand, a patient's support movably secured to said stand and provided with a track running beneath said support, an X-ray tube-supporting element upon said track, said element being adapted to be moved with said support in the adjustment of the latter and having a tiltable section for holding an X-ray tube, an X-ray tube in said element and tiltable therewith, a fluorescent screen mounted upon the opposite side of said support and adapted to be freely rotated in its mounting in a plane parallel to said support, and means for effecting a simultaneous movement of said screen and said tube-supporting element longitudinally of said table.

4. An X-ray photographic and fluoroscopic table comprising a stand, a patient's support journaled in said stand, a track beneath said support and in juxtaposition thereto, an X-ray tube-carrying element on said track and provided with a tube-engaging portion tiltable relatively to said support, an X-ray tube in said portion and tiltable therewith, a fluorescent screen, a supporting means for said screen in juxtaposition to said support, and means for effecting the simultaneous movement of said screen-supporting means and said element, said tube and tube-engaging portion being adapted to be tilted angularly to said screen.

5. The combination with an X-ray photographic and fluoroscopic table comprising a stand, a patient's support movably mounted in said stand and having a track therebeneath, an X-ray tube-supporting member upon said track, a fluorescent screen at the opposite and upper side of said support, means for effecting the simultaneous movement of said tube-supporting member and of said screen longitudinally of said support, and a single counterbalancing means for said member and said screen, of a tube-holding portion upon said tube-supporting member, and a tube therein, said supporting member admitting of the tilting of the tube angularly to said patient's support and to said screen.

6. The combination with an X-ray photographic and fluoroscopic table comprising a stand, a patient's support movably mounted in said stand and having a depending track

portion, an X-ray tube-supporting member disposed on said track and movable lengthwise of said support, a fluorescent screen at the opposite side of said member and movable lengthwise of said support, and means for moving said screen and said member transversely of said support, of a holding portion for an X-ray tube disposed in said member and tiltable therein, and a tube in said holding portion.

7. An X-ray photographic and fluoroscopic table comprising a stand, a patient's support movably mounted in said stand and having a depending track portion, an X-ray tube and a tube-supporting member disposed in said track and movable with said support in the adjustment of the latter to different positions, said member comprising a tube holder for said tube conjointly movable angularly with said tube with respect to said patient's support and lengthwise thereof, a standard for a fluorescent screen, and a fluorescent screen on said standard and on the opposite side of said support and also movable lengthwise thereof, said screen being freely movable on said standard in a plane parallel to said support.

8. In a fluoroscopic table, the combination of a patient's support, a holder for a fluorescent screen longitudinally movable on said patient's support, and a fluorescent screen mounted upon said holder, said holder comprising standards perpendicular to the top of said patient's support, a yoke slidable on said standards and having a portion projecting in the direction of said table top to provide a support for said screen, said screen being pivotally supported on said yoke whereby to provide for free rotation of said screen in a plane parallel to said patient's support.

9. In a fluoroscopic table, the combination of a stand, a patient's support movably mounted on said stand, a carriage for longitudinal movement on said support, a standard for a fluorescent screen secured to said carriage and having a portion extending in the direction of said patient's support, a holder for a fluorescent screen pivotally disposed upon said inwardly extending section of said standard, and a fluoroscopic screen tiltably disposed in said holder, said holder and screen being adapted to be moved in a plane parallel to said table top.

10. In a fluoroscopic table, the combination of a patient's support, a carriage for longitudinal and transverse movement parallel to said support, a standard upon said carriage and perpendicular to the top of said patient's support, a yoke slidably disposed upon said standard and having an end with an inwardly extending section, a tiltable cross bar in said end, a fork pivotally disposed upon said cross bar, and a fluorescent

screen disposed in said fork and adapted to be freely moved over said top in a plane parallel thereto.

11. In a fluoroscopic table, the combination of a stand, a patient's support movably mounted in said stand, a track under said support, a standard for a fluorescent screen disposed on said track, a fork therefor, a fluorescent screen tiltably disposed in said fork, and connecting means intermediate said standard and said fork comprising a yoke adapted to be moved upon said standard and having a tiltable part disposed at one end, and a slidable element having two parts, one part being disposed upon said tiltable part and the other at the end of said fork, the said connection between said fork and said standard admitting of said screen being freely moved on an axis adapted to be adjusted from the perpendicular to transverse of said table top.

12. An X-ray photographic and fluoroscopic table comprising a stand, a patient's support in said stand and having a depending track parallel to the top of said table, an X-ray tube-supporting member on said track and adapted to be moved lengthwise of said support, a tube-holding portion secured in said member, an X-ray tube in said holding portion, a fluorescent screen at the opposite side of said patient's support and disposed in a standard perpendicular to the top of said table and movable on said track, and connecting means intermediate said standard and said tube holding member for simultaneous movement lengthwise of said support, said standard having a section perpendicular to said table top, a yoke movable up and down said perpendicular section, a tiltable part at the inner end of said yoke, a fork for said screen, and a slip joint intermediate said yoke and said fork.

13. An X-ray photographic and fluoroscopic table comprising a stand, a patient's support journaled upon said stand and adapted to be moved in a vertical plane, a track depending from said support, an X-ray tube-supporting member upon said track, a fluorescent screen at the opposite side of said support, and a standard perpendicular to the top of said table for said screen and including a plurality of adjustable connecting means adapting said screen to perpendicular, lateral, longitudinal, and angular adjustments relative to said support and free rotative movement upon axes perpendicular and parallel thereto, said adjustment means comprising a member slidable upon said standard and having a pivoted part disposed therein, and a fork for holding said screen and journaled in a member secured to said pivoted part and comprising faces adapted to be adjusted relatively.

14. An X-ray photographic and fluoroscopic table comprising a stand, a patient's

support journaled in said stand and provided with a track therebeneath and running lengthwise thereof, and an X-ray tube and tube-supporting element upon said track mounted for movement thereon and movable with said support in the adjustment of the latter, said element comprising a shield support, and a shield tiltably mounting said tube in said support, said shield being of a generally uniform thickness of material opaque to X-rays and in close proximity to said tube over its entire extent.

15. An X-ray photographic and fluoroscopic table comprising a stand, a patient's support journaled upon said stand, a track beneath said support and parallel thereto, an X-ray tube-carrying element movable on said track and provided with tiltable tube-supporting members, and an X-ray tube, said tube and tube-supporting members being rockingly movable on an axis parallel to said patient's support, and said tube-supporting members comprising a shield of sections of material opaque to X-rays of a generally circular configuration at their ends to provide for their support in said element.

16. An X-ray photographic and fluoroscopic table comprising a stand, a patient's support journaled in said stand and having a depending track thereon, an X-ray-tube-supporting member disposed upon said track and provided with shield engaging portions adapted to be rocked in said member, a shield of material opaque to X-rays disposed on said member, the material of which is in close proximity to a tube, an X-ray tube, and a single counterbalance for said member and the parts carried thereby.

17. An X-ray photographic and fluoroscopic table comprising a stand, a patient's support journaled in said table and adapted to be moved in a substantially vertical plane, said support being provided with a depending track portion, an X-ray-tube-supporting member disposed on said track beneath said support and movable lengthwise of said support, a shield of material opaque to X-rays for enclosing a tube, a tube within said shield, shield holding means upon said support and adapted to be tilted relatively thereto, and a single counterbalance for said tube supporting member and the parts carried thereby, said shield comprising sections of a material of substantially uniform thickness arranged in close proximity to the walls of the enclosed tube and being of the same general contour as said tube, each end of said shield comprising a cylindrical portion for providing bearings for the movement thereof.

18. An X-ray photographic and fluoroscopic table comprising a stand, a patient's support journaled in said stand and having a depending track portion, an X-ray tube-supporting member disposed in said track,

- 5 said supporting member comprising a shield support, a shield of a single thickness of material opaque to X-rays and tiltably disposed in said shield support, a fluorescent screen 10 in the opposite side of said patient's support and movable lengthwise of the latter, means 15 for effecting the simultaneous movement of said member and screen lengthwise of said support, and a single counterbalance for said screen and said tube supporting element. 20
19. In a fluoroscopic table, a stand, a patient's support journaled in said stand, an X-ray tube, and a fluorescent screen mounted at the side of said support for free rotation in a plane parallel to said support, said screen extending across and being adapted to be moved lengthwise of and tilted angularly to the surface of said patient's support, said screen being connected to said support by a plurality of adjustable means comprising a sectional standard adapted to telescope, and a fork in which said screen is tiltably disposed and having a friction joint connection with one of the sections of said standard. 25
20. In a fluoroscopic table, a stand, a patient's support journaled in said stand and adapted to be moved in a vertical plane, an X-ray tube, a fluorescent screen, and means for mounting said screen upon said support, said mounting means for said screen comprising a standard at the side of said support, a yoke adapted to telescope on said standard and having a friction joint member pivoted therein, and a fork journaled in said friction joint member and in which said screen is tiltably disposed. 30
21. In a fluoroscopic table, a stand, a patient's support journaled in said stand, a carriage movable parallel to the top of said support, a screen standard movable with said carriage, a fluorescent screen, and connecting means intermediate said standard and said screen, said connecting means including 35 a part terminating in a tilttable member and providing a support for one part of a slip joint, and a part supporting said screen and journaled in the other half of said slip joint, said tilttable member having means limiting its movement beyond predetermined angles. 40
22. In a fluoroscopic table, a stand, a patient's support journaled in said stand, an X-ray tube, holding means for a fluorescent screen on said support, and a fluorescent screen in said holding means and having a universal movement relatively to said patient's support, said holding means comprising 45 a standard, a carriage perpendicularly adjustable thereon, a screen supporting member in which said screen is rockingly disposed, and a connecting member having a plurality of slip joints, the planes of the abutting faces of which are perpendicularly disposed. 50
23. A combined fluoroscopic and radiographic table comprising a stand, a support transparent to X-rays mounted in said stand and having plate holding tracks upon one side thereof, one of said tracks being angularly movable from engagement with said support to enlarge the field of fluoroscopic vision. 55
24. A radiographic and fluoroscopic table comprising a stand, a patient's support transparent to X-rays thereon, and cassette holding members disposed on one side of said support, the outermost of said members comprising track portions and being permanently secured to said support, and the intermediate member having track portions on both sides thereof and being removable from proximity to said support whereby to provide an enlarged field of vision for fluoroscopic examination. 60
25. A combined fluoroscopic and radiographic table comprising a stand, a patient's support transparent to X-rays disposed on said stand, transverse plate holding members permanently affixed to said support stand, and a pivoted member having track portions on opposite sides thereof intermediate said fixed members and having an angular adjustment relative to said support adapting it to be disposed in a manner not obstructing the field of fluoroscopic vision of said support, said pivoted member when parallel to said fixed members cooperating therewith to hold a plate in photographing position on either or both sides thereof. 65
26. An X-ray photographic and fluoroscopic table comprising a stand, a patient's support journaled upon said stand and having a longitudinal track, an X-ray-tube-supporting member adapted to be moved lengthwise of said support on said track and conjointly movable with said support in the adjustment of the latter, a fluorescent screen at the opposite side of said support and disposed upon a standard, means connecting said screen standard and said tube-supporting member one to another for simultaneous movement lengthwise of said support, said tube supporting member comprising a tube holding portion disposed thereon for axial movement admitting of said tube being moved independently of the movement of said screen standard and tube supporting means. 70
27. An X-ray photographic and fluoroscopic table comprising a stand, a patient's support journaled upon said stand, a track depending from said support, an X-ray-tube-supporting member upon said track, a fluorescent screen at the opposite side of said support, and means for effecting a simultaneous movement of said tube supporting member and said screen, said X-ray-tube-supporting member comprising a frame, a tube holding section tiltably mounted in said 75

frame, and a tube adapted to be rocked jointly with said holding section.

28. An X-ray photographic and fluoroscopic table comprising a stand, a patient's support upon said stand and provided with a track beneath said support and running lengthwise thereof, an X-ray tube supporting element disposed upon said track for movement thereon, said element including a frame, tube holding members upon said frame, a shield rockingly disposed in said members, and a tube, a standard at one side of said support and having a tilttable part adapted to support a screen fork, means for connecting said tube supporting element and said standard for simultaneous movement, a fork for said screen journaled in said tilttable part, and a fluorescent screen tiltably disposed in said fork, said screen and said tube each being adapted to be rocked on axes parallel to said support.

29. An X-ray photographic and fluoroscopic table comprising a stand, a patient's support disposed in said stand, a track beneath said support and parallel thereto, an X-ray-tube carrying element movable on said track and comprising a body, a track, spaced supporting members, a tube holding portion, the latter being adapted to be rocked in said supporting member, a tube, a screen holding standard on said support, means for connecting said standard and said tube carrying element one to another for simultaneous movement lengthwise and crosswise of said support, and a fluorescent screen disposed on said standard.

30. An X-ray photographic and fluoroscopic table comprising a stand, a patient's support upon said stand and having a depending track parallel thereto, an X-ray tube supporting member on said track having a section movable lengthwise of said support and a second section adapted to be moved transversely of said first mentioned section, the latter having tube holding members, a tube enclosing portion in said members and adapted to rock therein, and a tube, a standard for a fluorescent screen movable lengthwise and crosswise of said support, means for effecting the simultaneous movement of said member and said standard lengthwise and crosswise of said support, and a fluorescent screen disposed in said standard.

31. An X-ray photographic and fluoroscopic table comprising a stand, a patient's support upon said stand and having a depending longitudinal track thereon, an X-ray tube supporting member upon said track and having a rail section, a body portion movable transversely of said support on said rail section, a portion for holding a tube casing, a tube casing tilttable therein, and a tube, a standard upon said support adapted to axially support a screen and movable

lengthwise of said patient's support, means for effecting simultaneous longitudinal and transverse movement of said member and standard, and a screen tiltably disposed in said standard the axis of revolution of said screen being in a plane parallel to the maximum dimension of the patient's support.

32. An X-ray photographic and fluoroscopic table comprising a stand, a patient's support upon said stand, a track arranged parallel to said support, an X-ray tube supporting member movable on said track and comprising a section having transverse rails, a body section movable upon said transverse rails, and a tube holding element pivotally secured to said body and adapted to permit the rocking of said element and of a tube therein relatively to said support, a standard upon said stand and movable lengthwise and laterally of said support, and a fluorescent screen in said standard.

33. An X-ray photographic and fluoroscopic table comprising a stand, a patient's support in said stand, a longitudinal track upon said support, an X-ray tube supporting member upon said track, said member comprising a rail portion adapted to be moved longitudinally of said support, a body portion disposed upon said rail portion and movable transversely of said support, and a tube holding element pivotally secured to said body and adapting a tube contained therein to be rocked concurrently therewith, and a fluorescent screen and standard therefor upon the opposite side of said support, said standard and said tube supporting member being relatively adjustable in a direction crosswise of said support.

34. An X-ray photographic and fluoroscopic table comprising a stand, a patient's support upon said stand, a track upon said support and parallel thereto, an X-ray tube supporting member on said track and comprising a rail section, a body portion adjustable upon said rail section, and a tube holding element pivotally secured to said body, a standard at the opposite side of said support and comprising a plurality of relatively adjustable sections, a fluorescent screen on said standard and supported upon one of said sections, and means for effecting simultaneous movement of said member and said standard lengthwise of said support, said sections being joined one to another to provide universal movement for said screen.

35. An X-ray fluoroscopic table comprising a stand in which an X-ray tube is disposed, a patient's support upon said stand, a standard upon said support including sections extending over and beneath said patient's support, and a fluorescent screen mounted upon said standard, said standard comprising sections telescoping upon one another, a tilttable member in one of said sections, a slip joint connection disposed on

- 35 said tilttable member, and a yoke journaled in one of the parts of said slip joint and adapting said screen to be rotated in a plane parallel to the plane of said patient's support and with its surface at an angle to the surface of said support or to be tilted away from said patient's support.
36. An X-ray fluoroscopic table comprising a stand, an X-ray tube disposed in said stand, a patient's support upon said stand, a standard at one side of said support comprising a plurality of freely movable sections, and a fluorescent screen disposed in said standard, movement of said standard and relative adjustment of said sections adapting said screen to be moved lengthwise and crosswise of said support and in planes at angles to the plane of said support, the axes of such angular movements being perpendicular to and transversely and longitudinally parallel to said patient's support, said adjustable sections including telescoping parts, a pivoted slip joint on one of said parts, and a fork tiltably holding said screen and journaled in one part of said slip joint.

37. An X-ray fluoroscopic table comprising a stand, an X-ray tube disposed in said stand, a patient's support upon said stand, a standard movably mounted upon said support at one side thereof and adapted to extend above said patient's support, and a fluorescent screen disposed at a point substantially midway its length in said stand and adapted to rock thereon, said stand comprising a plurality of sections joined together to provide free relative movement, one of said sections being adapted to telescope upon another and having at its upper end a tilttable support, and another of said sections tiltably holding said screen and being journaled in a friction disk member disposed upon said tilttable support, said screen being adapted to move in said stand in directions perpendicular, lateral, longitudinal, and at angles to said support, the angular movements of said screen including movements upon a plurality of axes parallel to said support and upon an axis perpendicular thereto.

JULIUS B. WANTZ.
